PORTABLE COOLING UNIT

Alfredo Mendez, Chicago, Ill.

Application August 25, 1953, Serial No. 376,428

3 Claims. (Cl. 62—140)

My invention relates to a novel and improved cooling apparatus which, while primarily intended for use in cooling the interior of motor trucks and truck trailers, is also adapted for other uses, and further may embody a stove or other heating unit which is fueled by gas obtained from the cooling unit, per se.

Truck cooling apparatus according to prior developments is very expensive, and it is an object of the present invention to provide a greatly simplified unit which will cost but a fraction of the cost of prior apparatus, and which further can be readily applied and removed according to whether or not a particular truck's cargo is perishable or not.

Additionally, the present invention contemplates, as hereinbefore intimated, a combination cooling apparatus and stove or cooker, which is fueled by gas from the cooler unit so that the truck driver can make coffee or heat up a can of soup upon occasion, if he so desires.

It is also an object of the invention to furnish apparatus as characterized, which is strong and durable in construction, involves a minimum number of easily assembled parts, is highly efficient in operation, and requires the use of no moving parts other than a motor-driven fan.

The invention also resides in certain novel features of construction, combination and arrangement of parts and in modes of operation, all as will be understood and appreciated by those versed in the art from a reading of the following descriptive matter dealing with the embodiment which is illustrated in the accompanying drawings.

Although a now preferred form of the invention has been chosen for illustration and description, in accordance with the requirements of the patent statute, it will readily be perceived that various changes and modifications may be made therein within the spirit and scope of the subject matter claimed hereinafter.

In the drawings, wherein the same reference characters have been used to designate the same parts throughout the several views—

Fig. 1 is a broken view partly in section, and largely diagrammatic, showing the application of the apparatus to a truck trailer;

Fig. 2 is a front elevational view of the novel cooling unit, per se, which is embodied in my apparatus;

Fig. 3 is a rear elevational view of the same;

Fig. 4 is a vertical sectional view taken on the line 4—4 of Fig. 3;

Fig. 5 is a perspective view of the base member which is incorporated in the unit of Figs. 2, 3 and 4; and

Fig. 6 is a perspective view of one of the coil-carrying side members of said unit.

Referring specifically to the drawings, Fig. 1 shows the apparatus applied to a familiar form of tractor-drawn truck trailer, the tractor having the usual cab, as shown.

In carrying out the invention, a supply tank A for propane or other hydrocarbon which is normally gaseous at atmospheric pressures, is conveniently supported by

2

the bracket carried shelf A' secured to the interior front wall I of the trailer, said tank having the usual filling opening B. A supply line C leads from the bottom portion of the tank A to the coil 14 of the cooling unit F by way of the usual expansion valve 32 which gasifies the liquid propane. Cooling unit F is secured to the shelf G which is supported by brackets H carried at the interior side of trailer front wall I. As will be understood, the propane in tank A will be under pressure and compressed air can be supplied thereto in the usual way if necessary.

In the Fig. 1 showing, the gas from the cooling coil 14 is discharged through a pipe L to a burner or cooker M secured to the exterior side of the front wall I of the trailer, conveniently adjacent to the tractor cab. The gas can simply be allowed to escape while the truck is in transit, or the cooker can be lighted to consume the gas and to heat coffee, etc., when the truck has stopped. The cooker M provides a flame guard O about the burner end of pipe L.

A thermostatically controlled cutoff valve E is incorporated in the propane supply line C from tank A, and it is closed and the circuit of the fan driving motor 25 of the cooling unit F is opened by the thermostat E' in the trailer when the interior temperature thereof is correct.

A manually operated cutoff valve D in line C from tank A may be made accessible through hole J in the front wall I of the trailer, there being a pivoted closure K therefor as shown. Also, if desired, there may be a manually operable cutoff N adjacent stove M.

As will be appreciated, the foregoing described arrangement is simply illustrative and the parts can be differently arranged, if desirable, or installed in a house or house trailer.

Referring now to the details of the cooler unit F per se, shown in Figs. 2, 3, 4, 5 and 6, same has as the main frame parts the pan-like base 10 of Fig. 5 and two upstanding, laterally spaced, and substantially duplicate, side units 12 (see Fig. 6).

The side units 12 are supported by the bottom 10a of said base, inwardly of the ends of the latter as shown in Figs. 3 and 4. Units 12 differ only in that one is a "left hand" unit so as to speak, and the other is a "right hand" unit, as will be made clear hereinafter.

The frame of the cooler unit F is completed by the fan and motor-carrying rear wall 15, and upper front molding 20 which has a part 20a which cooperates with a portion 15a of the rear wall 15 to support the removable closure 16.

Thus, the cooler unit frame comprises but six parts which are easily assembled and can be readily and cheaply made as stampings, all as will be readily understood as the description proceeds. Also, as a preliminary, it may be observed that the cooling coil 14 with expansion valve 32 is designed to be assembled with side members 12 as a unit.

Thus, referring in detail to the construction of the cooler unit, per se, it comprises the rectangular pan-like base 10 of Fig. 5, having the bottom wall 10a, the long front and rear walls 10b and the end walls 10c.

The two upstanding coil-supporting end wall units 11 of Fig. 6 are channel-like and have the spaced parallel front and rear walls 11a, 11b, respectively, which are connected by the coextensive cooling coil-supporting bight wall 11d and by the horizontal closure-supporting top wall 11c. The bight walls 11d of the units 12 define the end walls of the cooler unit F, as will be understood, and wide front wall portions 11a define the sides of the rectangular cool air discharge opening 29 at the front of said cooling unit F. The open lower ends of the end units 12 are supported by base 10 as shown in Fig. 3.

Fig. 6 shows the bight wall 11d of the end units F as provided with holes 13 for the passage of the cooling coil 14 as indicated in Fig. 3.

Referring to Figs. 3 and 4, the rear wall 15 of the cooling unit F is coextensive in height with the end units 12 and its sides overlie and are secured, as at 18, 19, to the rear flanges 11b of said end wall units 12. The lower end of the rear wall 15 rests upon the bottom wall 10a of base member 10, and it and the lower ends of the rear flanges 11b of said end units 11 are secured to the rear wall 10b of the base unit by machine screws or the like 17.

Figs. 2, 3 and 4 also show that the top of the rear wall 15 of the cooling unit F has the forwardly extending keeper groove-defining flange 15a for the rear edge of the removable top closure 16 which affords access to the coil 14 and expansion valve 32, to be referred to hereinafter. Machine screws 16a engaging in the top flange 11c of end units 11 cooperate with 15a to secure closure 16 in place.

Turning now to Figs. 2 and 4, it will be observed that the top of the rectangular front cold air discharge opening 29 is defined by the frame reinforcing molding member 20, while the bottom of said opening 29 is formed by the front flange or wall 10b of base member 10. As earlier pointed out, the sides of said air discharge opening 29 are defined by the wide flanges or walls 11a of the end wall units 11 of Fig. 6.

Fig. 4 also shows that the top edge of molding member 20 has a coextensive inturned flange 20a which supports the forward edge of top closure 16. Machine screws 16a and 20b secure molding 20 in place, the screws 20b engaging in the underlying walls or flanges 11a of the end units 11.

Referring to Figs. 3 and 4, the rear wall 15 of the cooling unit F has the opening 21 for at least partially receiving the fan 23 which is fast on the armature shaft 24 of the electric motor 25 whose casing is bolted as at 26 to the bracket 27. The bracket 27 extends across the rear wall opening 21 and has end feet 27a removably secured as at 28 to the rear unit wall 15. As will be noted, the fan 23 discharges toward the rectangular front opening 29 of Fig. 2, through the intervening cooling coils 14 which carry the usual closely spaced temperature-disseminating fins 14b, as shown.

As to inlet and outlet connections, etc., for the cooling coil 14, Figs. 3 and 4 show a conventional inlet coupling 30 for the supply line C from the tank A of Fig. 1, such inlet coupling registering with a hole 15b in rear wall 15. This inlet coupling 30 has a conventional connection 31 with a standard expansion valve 32 adjacent the top of the unit, and the gas discharge side of said expansion valve has a usual coupling connection 33 with the inlet proper 14a of cooling coil 14. Expansion valve 32 has the usual knurled regulating knob which registers with a hole 15c in rear wall 15. Discharge from coil 14 is through outlet coupling 34 shown in Fig. 3, as readily accessible behind one of the end unit flanges 11a.

The operation of the apparatus as described may be summarized as follows. Propane gas in liquid form under pressure from the tank A of Fig. 1 passes into the inlet fitting 30 of Fig. 3, is gasified by expansion valve 32 and delivered to coil 14 to cool same in the usual manner. The fan motor 25 will be driven by a battery or other means and may be controlled as stated, along with propane cutoff valve E by the thermostat E' located in the trailer or other place to be cooled.

Five gallons of propane will, with the use of my apparatus, adequately cool a large-sized trailer for more than three hours, and since propane is very cheap, costing only a few cents a gallon, the discharge of same to the atmosphere from the coil outlet 34 is more than compensated for by the cheapness of the unit, eliminating as it does the necessity for a cooling fluid circuit and

pump. Also as illustrated in Fig. 1, the propane discharge from cooling coil 14 may be to a burner or stove M which is available to the truck driver for heating coffee or soup.

Although the use of the apparatus in connection with trucks and truck trailers has been particularly stressed, the portability of the cooling unit per se readily adapts it for use in the refrigerators of house trailers or dwellings and otherwise, where a "bottled gas" (propane) supply is available.

In a house trailer, for instance, the unit with or without the motor and fan attachment, can be advantageously employed, the motor and fan unit being readily detachable, as will be noted. Thus the cooler unit can be put in an ordinary ice refrigerator, and connected to the trailer's propane supply tank to preserve breakfast food overnight, and the stove and flame guard M, O of Fig. 1 may take the form of a parking light or night light. The same use can advantageously be made of the unit at summer cottages when ice is not conveniently available, as propane gas can be bought cheaply and in large quantities and will "keep," whereas ice won't.

The aforesigned uses of the unit with or without the fan are merely examples of the utility of the unit. Many other uses will doubtless suggest themselves to those interested in air conditioning, refrigeration, etc.

The device is also admirably suited for use in house trailers, and for that matter in kitchens generally which become unduly warm when cooking operations are in progress. And when so used, the stove M of Fig. 1 can be employed for cooking purposes.

The cooling unit is very inexpensive, as will be appreciated, since it comprises but a few major frame parts all of which can be produced by simple stamping operations.

Having thus described my invention, what I claim is:

1. A portable cooling unit for trucks, truck trailers, house trailers, kitchens, dwelling and storage rooms, etc., comprising in combination a casing-like frame comprising a rectangular pan-like base having upstanding front, rear and end flanges, a pair of upstanding, laterally spaced and substantially channel form end wall units for said frame supported between said base flanges and providing longitudinally coextensive front and rear flanges, the front flanges of said end wall units being substantially wider than the said rear flanges, an upstanding rear wall for said cooling unit coextensive in height with said end wall units and providing a central fan receiving opening, said unit rear wall supported by said base member between the rear flange thereof and the lower ends of the rear flanges of said end wall units, fastening means securing said unit rear wall to said rear end wall unit and base member flanges, other fastening means securing said rear wall to said rear end unit flanges, a front panel element secured to and connecting the front flanges of the end wall units adjacent the top thereof whereby to cooperate with the latter and the front flange of said base unit to provide a rectangular cold air discharge opening at the front of said unit and occupying the major portion of said unit front in alignment with the fan-receiving opening of said unit rear wall, a cooling coil extending between said end wall units and having an inlet at one end and an outlet at the other end, said coil supported by said end wall units between said flanges to be protected thereby, there being an expansion valve in said coil adjacent the inlet thereof and having adjustment means operable through a hole in said unit rear wall, a removable top closure for said unit, said front panel having a substantially coextensive inturned flange at its upper edge cooperating with the upper ends of said end wall units to support said closure, a forwardly turned keeper flange at the top edge of said rear wall and overlying the rear edge of said closure, said end wall units having integral horizontal flange-connecting top portions, closure fasteners engaging the latter, a motor-carried fan secured

to said rear end member flanges and disposed opposite said fan-receiving opening therein, and said coil outlet lying behind the widened front flange of one of said end wall units to be protected thereby.

2. A portable cooling unit for trucks, truck and house trailers, rooms, refrigerators, etc., comprising a cooling coil adapted to receive under pressure a hydrocarbon which is normally gaseous at atmospheric pressures but liquid under pressures greater than atmospheric, said coil having an inlet at one end and an outlet at the other end, there being an expansion valve adjacent said coil inlet, a casing-like supporting frame for said coil and expansion valve, said frame including aligned upstanding substantially channel form side members having their bight portions arranged in spaced opposition to one another and through which convolutions of said coil extend, said bight portions supporting said coil inwardly of return bends thereof and rigidly secured thereto whereby the coil and side members constitute a unit, the outer limits of said return bends terminating short of the planes of the outer edges of the outstanding side member flanges whereby to be protected by the latter, separable top and bottom cross members connected to said side members, and said bottom member comprising a drain-providing pan providing upstanding side walls to which the side member flanges are attached.

3. In a portable cooling unit for trucks, truck and house trailers, rooms, refrigerators, etc., comprising a cooling coil adapted to receive under pressure a hydrocarbon which is normally gaseous at atmospheric pressures but liquid under pressures greater than atmospheric, said coil having an inlet at one end and an outlet at the other

end, there being an expansion valve adjacent said coil inlet; the combination of a casing-like supporting frame for said coil and expansion valve, said frame comprising upstanding laterally spaced side members to which said coil is rigidly secured, said coil and expansion valve disposed between the planes of the side edges of said side members with the coil adjacent the top of said frame, a pan-like base member included in said frame and having upstanding flanges and supporting said side members, means detachably securing said side members to said base flanges, a rear wall supported by and secured to said base and side members, a front wall element at the top only of said frame and concealing said expansion valve, said front wall element being detachably connected to said side members, and a removable top closure at least in part supported by said rear wall and by said front wall element, and at least in part secured by one of the latter.
